UNITED STATES PATENT OFFICE.

JOHN W. CLARK, OF PROVIDENCE, RHODE ISLAND.

APPARATUS FOR FORMING CORD SHEET MATERIAL.

Application filed March 12, 1923. Serial No. 624,479.

This invention relates to an improved method and apparatus for forming a cord sheet material particularly adapted for use in the manufacture of cord tires for automobiles and the like, and is an improvement upon the structure shown in my copending application Serial No. 604,928 filed Dec. 4, 1922.

The main objects of the invention relate to 10 the improvement of the method and apparatus generally and more particularly to providing an improved tension equalizing means as well as a novel form of guiding or spacing means which are designed to simplify the apparatus generally and render the process capable of more efficient operation.

As stated in my prior application above referred to, it is necessary in forming rubberized sheet material that the cords which are 20 incorporated therein be free or substantially free from moisture, and in order to conserve space and effect the complete drying of the cords before they are incorporated in the sheet material I find it advisable to wind the cords upon beams instead of taking the cords from creels as has been the practice in some cases heretofore. It is also desirable that the cords be spaced uniformly from each other when incorporated into the sheet material and that 30 all of the cords be under substantially uniform tension as the rubber is applied thereto.

In order to accomplish the objects above set forth, I propose to first wind the cord upon the conventional form of beam such as is well-known in the weaving art, and as a preliminary step to the forming of the sheet material, pass the cords from the beam over conventional drying rolls to a second beam upon which they are wound preparatory to the formation of the material. By making the drying of the cords preparatory to the formation of the sheet material a separate step in the process, I am enabled to more thoroughly and completely remove the moisture from the cords than would be possible if the drying were effected as an incident to the formation of the material, since, in general, a slower speed of travel for the cords over the drying rolls is required than is necessary or desirable in the formation of the material.

After thus drying the cords I pass them from the second beam, upon which they are wound after coming from the drying rolls, over members shaped to insure proper positioning of the cords relative to each other as

well as to slightly increase the tension on the centrally placed cords, and then progressively feed adjacent cords on opposite sides of one or more tension equalizing devices to separate adjacent cords from each other and impart uniform tension thereto. While the degree of tension upon the cord ends may be varied both by varying the degree of pull required in withdrawing the cords from the beam as well as by increasing or decreasing the number of tension equalizing devices employed I regard it as advisable in general to employ a moderate degree of tension, and am more particularly desirous of maintaining a substantially uniform tension on the several cords subject only to the necessary progressive variation of tension between the cord ends at the central portion and those located at the edges thereof. The cord ends thus substantially equally tensioned are preferably passed over a positioning or equalizing roll, the surface of which may be roughened, to effect a preliminary positioning of the cords in approximately the relative positions which they should occupy in the completed fabric and to overcome any undue slackness which may occur in individual cords. When the surface of the positioning roll is roughened as stated a more efficient equalizing of the tension is effected and a more positive positioning action results. From the positioning roll the cord ends are fed to the calender rolls for forcing or frictioning unvulcanized rubber into the surfaces thereof, but the cords are first contacted with a spacing or guiding member by passing adjacent cord ends on opposite sides of a stationary member which is provided with a plurality of grooves located upon opposite sides thereof, the grooves upon one side of the spacing member being off-set from the grooves on the opposite sides thereof in a direction longitudinally of the spacing member to an extent equal to one-half the desired horizontal distance separating alternate cords of the sheet material. The cords as they engage the grooves on opposite sides of the spacing member are thus displaced vertically above and below the normal plane of their travel and are positively spaced an equal distance from each other just prior to passing between the calender rolls. Thus there is

insured a proper laying of the cord ends relative to each other as they are delivered to the calender rolls for the frictioning of unvulcanized rubber into the surfaces of the cords and the interstices therebetween. As the sheet

- material emerges from the calender rolls it may be wound upon a roll with a strip of muslin or other similar fabric between adjacent layers, and, if desired, may be again 5 passed through a calender to friction an additional layer of unvulcanized rubber upon the side opposite to that receiving the major portion of the rubber during its first passage through the calender.
- 10 As an illustration of a form of apparatus which I may employ in carrying out my improved method of forming the sheet material attention is directed to the accompanying drawings wherein,
- 15 Fig. 1 is a diagrammatic sectional view of the apparatus,
- Fig. 2 is a view taken along the line 2—2 of Fig. 1,
- Fig. 3 is a view taken along the line 3—3 of 20 Fig. 1,
- Fig. 4 is a top plan view of a portion of the positioning or equalizing roll,
- Fig. 5 is a view taken along the line 5—5 of Fig. 1 and,
- 25 Fig. 6 is a top plan view of a portion of the guiding member showing the position of the cord ends relative to the grooves.
- In the form of apparatus illustrated here- 30 with 1 designates a beam of conventional form for supporting a plurality of ends in such a manner as to permit their progressive withdrawal in substantially parallel relation to each other and in substantially the same plane as they pass from the beam. As the 35 cord ends A are drawn from the beam 1 they are first passed over a stationary member 2 provided with a curved face 3, the curvature of which is slightly convex transversely of the path of travel of the cords as shown in somewhat exaggerated form in Fig. 3 of the 40 drawings. After passing over the member 2 the cord ends are passed under a similar member 4 which is provided with a curved face 5, the curved surface 5 being so positioned as to be engaged by the cord ends 45 as they pass from contact with the member 2 and move forwardly through the apparatus. The curved surface 5, like the curved surface 3, is slightly convex longitudinally of the 50 member 4 as is more clearly shown in Fig. 2 of the drawings. The members 2 and 4 serve to draw the cord ends into position and impart a slightly greater tension to the central cord ends than to those located at the edges of the web to prevent bagging of the 55 cord ends located at or near the central portion of the web.
- As the cord ends pass from the member 4 they are positioned in substantially the 60 same horizontal plane, and the centrally located cord ends are under slightly greater tension than the cords located at the edges, the increase in tension from each edge towards the center being gradual by reason of the 65 convexity of the surfaces 3 and 5 of the mem-

bers 2 and 4. In order to equally tension the cord ends, subject to the variation in tension from the center to the edge portions as above noted, and prevent interference or overriding of adjacent cords the adjacent cord ends are displaced vertically above and below their normal plane of travel and passed above and below a stationary member 6 with which they frictionally engage as they are drawn forwardly.

In other words alternate cord ends are displaced upwardly to pass over the member 6 while the remaining cord ends are displaced downwardly to pass below the member 6. The degree of displacement of the cord ends passing above the member 6 from their normal path of travel is substantially equal to the degree of displacement of those passing below the member 6. A plurality of tensioning members 6 may be employed and the number may be varied as desired dependent upon the degree of tension required and the material employed. In the present instance three of these tensioning devices are shown but it is to be understood that a greater or less number may be employed as conditions may require or circumstances render expedient.

The cord ends which are passed above the first member 6 are preferably passed below the second member, while the cord ends passing below the first member 6 are passed above the second member. This alternate displacement downwardly and upwardly of each cord end below and above adjacent members 6 is preferably continued throughout the series of tensioning members, thus imparting the desired degree of tension to the cord ends while at the same time equalizing such tension and insuring that the several cord ends occupy their proper positions relative to the remaining cords to prevent a portion of any cord from becoming in any way entangled with or overlying the cord next adjacent thereto.

It will be noted in connection with the contacting of the several cord ends with the tensioning devices 6 that each cord end contacts with each equalizing device through substantially the same extent of its travel as every other cord end whereby the degree of frictional resistance encountered by the several cord ends is substantially the same to effect an equalization of the tension thereon.

From the tensioning members above described the cord ends are passed beneath a guide roll 9, over a positioning or tension equalizing roll 10, and below a guide roll 11, all of which rolls may be rotatably supported by suitable bearings in frame members 12, which in the present instance are two in number and located at opposite ends of and serve as supports for the beam 1 as well as the various elements traversed by the cord ends for supporting the beam and said elements in

proper position for guiding the cord ends as they pass from the beam to the calender rolls. Only one of these frame members is shown in the diagrammatic sectional view illustrated in Fig. 1, the cooperating member being positioned opposite thereto and having similarly positioned bearings for supporting the beam 1 and the rolls 9, 10 and 11, as well as means for fixedly supporting the opposite ends of the members 6 and 15. The members 12 may each be provided with suitable openings for giving access to the various elements supported thereby as is well-known in frames of this character. The positioning roll 10 is preferably provided with a roughened surface which may be applied or formed in any desired manner such as, for example, by giving the same a surfacing of sandpaper, whereby the roll exerts a slight gripping action upon the cords passed thereover and tends to hold them against slippage thus insuring a substantially equal speed of travel on the part of the several cord ends. As the cord ends are drawn over the roll 10 the roll is rotated by the gripping action of the cords on the surface of the roll, which is increased by roughening the surface of the roll. The inertia of the roll tends to cause an equal pull upon each cord between the roll 10 and the calender and thus compensate for any looseness which may develop in any one or more cord ends. The pull upon the cord ends in rotating the roll 10 also has a tendency to prevent any cord from overriding the adjacent cord. After passing beneath the roll 11 alternate cord ends may be passed below and above a member 15 similar in all respects to the tensioning members 6 and as they pass from contact therewith the cord ends passed above the member 15 may be displaced downwardly to pass below a second similar member 15 while those cord ends passing below the first member 15 are passed above the second member 15. While two tensioning members 15 are shown as interposed between the roll 11 and the spacing member 16 it is to be understood that a greater or less number of tensioning members may be located between the roll 11 and the spacing member 16, or that the use of tensioning members at this point may be dispensed with altogether if desired. From the tensioning members 15 alternate cord ends passing beneath the last member 15 are displaced upwardly and pass over a fixed spacing member 16 so as to lie in grooves 17 formed in the upper face of the member 16, while the cord ends passing above the last tensioning member 15 are passed below the spacing member 16 and are guided by grooves 18 formed in the under face of the member 16. The grooves 17 on the upper face of the member 16 are offset from the grooves 18 longitudinally of the member 16 a distance equal to one-half of the distance separating adjacent grooves 17, and the grooves 17 are spaced

from each other a distance substantially equal to the distance separating adjacent grooves 18 from each other. In this way the cord ends are guided and spaced an equal distance from each other as they pass between the rolls 70 of the calender. From the spacing member 16 the cord ends pass directly to a calender 20 which comprises a frame 21, and rolls 22, 23 and 24.

The rolls 22, 23 and 24 are rotatably supported in suitable bearings carried by the frame 21 and are positively driven after a manner well-known in the art. Unvulcanized rubber B is fed between the rolls 22 and 23 as shown in the drawings whereby the rubber is drawn between the rolls and forced out by pressure into a relatively thin sheet which adheres to the roll 23 by which it is carried into contact with the cord ends A as they pass between the rolls 23 and 24 after leaving the spacing member 16. The rolls 23 and 24 may be driven at slightly different surface speeds which results in a slight slippage between their contacting surfaces whereby the unvulcanized rubber is frictioned into and between the several cords to hold the same in proper position relative to each other and form a continuous sheet composed of a plurality of parallel cords held together and substantially covered by unvulcanized rubber. It will be seen upon reference to Fig. 1 of the drawings that the cords passing over the upper surface of the guiding member 16 contact with the layer of rubber carried by the roll 23 slightly in advance of the cords which pass below the member 16 whereby the cords passing above the member 16 become slightly embedded in the layer of rubber and as the cords are drawn between the calender rolls a small quantity of rubber is forced between the adjacent cords. The cord fabric C, formed by frictioning rubber into and between the parallel cords, passes around the roll 24 and is continuously wound upon a roll 25, a sheet of muslin or other similar material D being drawn from the roll 26 and wound between adjacent layers of the rubberized material. If desired the rubberized sheet material thus formed may be again passed through a calender with the sides reversed to friction a suitable quantity of rubber into that side of the cords which received the minimum coating of rubber during the first passage through the rolls, and a thin layer of rubber may be laid upon one or both sides of the material.

The guiding or spacing member 16 and roll 26 may be supported by brackets 27, and 28 carried by the frame members 12, while the roll 25 may be supported by brackets 29 from the calender frame after the manner shown in the drawings.

The beam 1 is preferably supported in bearings carried by the frame members 12 and each end of the beam may be provided with a

circular shoulder 31 to receive a strap 32. One end of the strap 32 is anchored as at 33 and the opposite end thereof is secured as at 34 to a lever 35 pivoted to the frame at 36 and provided with a sliding weight 37 whereby the tension upon the cord ends as they are drawn from the beam 1 may be increased or diminished as desired by varying the position of the sliding weight upon the lever 35.

10 Although the above described means for imparting tension to the cord ends as they are withdrawn from the beam has been illustrated as one arrangement of means which may be adopted for this purpose, it is to be understood that various other suitable mechanisms may be adopted for this purpose as may be found desirable.

While I propose to substantially dry the several cord ends before they are placed upon 20 the beam 1 for incorporation into a sheet material, the particular form of apparatus employed for drying the cords is not illustrated as any suitable means may be employed for that purpose, such, for example, as an arrangement of drying rolls similar to that shown in my copending application.

It will be seen from the above description that the apparatus employed for making the cord sheet, as well as the method for forming 30 the same embodies certain important improvements over that shown in my copending application tending to simplify the method of operation and insure a more certain positioning of the cord ends as well as 35 more uniform tensioning of the cords.

While in the specification and certain of the claims mention is made of the step of frictioning unvulcanized rubber into the cord ends it is to be understood that such expressions are not to be construed in a limiting 40 sense but as embracing broadly the forcing or frictioning of the rubber into the surface of the cords as well as into the interstices therebetween to bind the cords into a sheet 45 suitably rubberized for use in the manufacture of cord tires.

What I claim is:—

1. The method of making rubberized cord sheet material for use in the manufacture of 50 cord tires which comprises, progressively withdrawing a plurality of unwoven cord ends from a holding member, passing said cord ends over a stationary tensioning member having a longitudinally convex surface for imparting progressively increased tension to the cord ends from the edges towards the center, vertically displacing adjacent cord ends in opposite directions from their normal plane of travel while guiding the same to insure a proper relative spacing of said cords from each other in a direction transversely of 55 their direction of travel, returning said cords into a substantially common plane and frictioning unvulcanized rubber into and between

said unwoven cords while the said cords are 60 in a substantially common plane.

2. In a method of making rubberized sheet material for use in the manufacture of cord tires the steps which comprise, withdrawing a plurality of cord ends from a supporting means, imparting progressively increased tension to the cord ends from the edges towards the center, vertically displacing the cord ends alternately in opposite directions from their normal plane of travel while contacting said cords with a stationary member to space each cord end from its adjacent cord, and forcing unvulcanized rubber between said unwoven cords to form a sheet.

3. In an apparatus of the character described, a beam for supporting a plurality of cord ends, a member provided with a convex surface engageable by said cord ends to impart progressively increased tension to said cord ends from the edges towards the center, 80 a tensioning member engageable upon opposite sides by said cord ends to increase the tension upon said cords, a guiding member provided with means located upon opposite sides thereof for engaging the cords and spacing them a substantially uniform distance from each other in a direction transverse to their path of travel, and means for forcing unvulcanized rubber between and around said cord ends.

4. In an apparatus of the character described, a beam for supporting a plurality of cord ends, tensioning members each of which is engageable upon opposite sides by said cords after they are drawn from the said beam to tension the said cords, a tension equalizing roll, and a guiding member provided with means upon opposite sides thereof for engaging the cords and spacing them a substantially uniform distance from each other in a direction transverse to their path of travel.

5. In an apparatus of the character described, means for supporting a plurality of cord ends, means for tensioning said cord ends as they are progressively withdrawn from the supporting means, and a guiding member provided with spaced grooves located upon opposite sides thereof for guiding said cord ends, the grooves upon one side of said guiding member being offset with respect to the grooves upon the opposite side thereof in a direction longitudinally of said guiding member.

6. In an apparatus for forming cord sheet material, means for supporting a plurality of cord ends, means for tensioning said cord ends as they are progressively withdrawn from the supporting means, a guiding means provided with spaced grooves located upon opposite sides thereof for guiding said cord ends, the grooves upon one side of said guiding member being offset with respect to the grooves upon the opposite sides thereof in a

direction longitudinally of said guiding member, and means for forcing unvulcanized rubber into and around said cords.

7. In an apparatus for forming cord sheet material, means for supporting a plurality of cord ends, stationary means comprising a stationary member provided with a longitudinal convex surface for imparting progressively increased tension to the cord ends 10 from the edges towards the center as they are withdrawn from the supporting means, a rotatable member engageable by said cord ends and operable to eliminate undue variations in tension between the various cord ends, 15 means for spacing said cord ends a substantially uniform distance from each other, and means for forcing unvulcanized rubber into and around said cord ends.

8. In an apparatus of the character described, a beam for supporting a plurality of cord ends, means for tensioning said cord ends as they are progressively withdrawn 20 from the beam, a guiding member provided with spaced grooves located upon opposite sides thereof for guiding said cord ends, the grooves upon one side of said guiding member being offset with respect to the grooves 25

upon the opposite side thereof in a direction longitudinally of said guiding member, and pressure rolls for drawing said cord ends 30 from said beam and over said tensioning means and guiding member.

9. A guiding device for directing a series of unwoven cords into contact with a layer of unvulcanized rubber comprising a member provided with means located upon opposite sides thereof for engaging the cords and spacing them a substantially uniform distance from each other in a direction transverse of their path of travel. 40

10. A guiding device for directing a series of unwoven cords into contact with a layer of unvulcanized rubber comprising a member provided with spaced grooves located upon opposite sides thereof for engaging alternate 45 cords, the grooves upon one side of said guiding member being offset with respect to the grooves upon the opposite side thereof in a direction longitudinally of said guiding member. 50

In testimony whereof I have affixed my signature.

JOHN W. CLARK.
